BATHTUB FIXTURE

Albert V. Redmond and Theodore P. Kersjes,
Kalamazoo, Mich.

Application January 13, 1933, Serial No. 651,472

2 Claims. (Cl. 4—191)

The main objects of this invention are:

First, to provide an improved bath tub drain fixture which is adapted to receive the discharge from the overflow pipe and is arranged so that the trap entrance is in communication with the drain, thereby providing ready access to the trap for cleaning and the like.

Second, to provide an improved combined overflow and supply nozzle fitting for bath tubs and

10 the like.

Third, to provide an improved outside combined overflow and supply fitting for bath tubs and the like.

Fourth, to provide a bath tub with means 15 whereby the combined drain and overflow trap may be cleaned without the use of panels and the like.

Objects relating to details and economies of 20 our invention will appear from the description to follow. The invention is defined and pointed out in the claims.

A structure which is a preferred embodiment of our invention is illustrated in the accompanying drawing, in which:

25 Fig. 1 is a fragmentary vertical section of a building having a built-in bath tub embodying the invention.

Fig. 2 is an enlarged fragmentary vertical section of the tub and fittings.

30 Referring to the drawing, 1 indicates floor joists which support a floor 2 and wall studs 3. The bath tub 4 is built or set in the bathroom 5 in a suitable manner, the interior of the room above the tub being shown as covered with tile 6. 35 Fig. 7 illustrates a soil pipe which is mounted on the vertical drain pipe 8 and concealed in the space 9 of the wall 10. The water supply pipe 11 is provided with a valve 12 provided with a handle or hand wheel 13.

40 The bottom 14 of the tub 4 is provided with a drain opening 15 surrounded by an annular recess 16. A bushing 17 is disposed through the opening 15 and is provided with an annular flange 18 which is received by the recess 16. A strainer or 45 drain plate 19 is secured to the flange 18 by screws 20. A drain fitting 21 having a chamber 22 is threaded to the bushing 17 with the chamber 22 disposed directly below the opening 15. Washers or gaskets 23 and 24, respectively, are disposed between the flange 18 and the bottom 14 of the tub and between the latter and the top of the fitting 21 for preventing leakage. A trap 25 is connected to the bottom of the fitting 21 with the trap entrance 26 opening to the chamber 22 50 and in substantially vertical alignment with the

drain opening 15. The exit of the trap 25 is connected to the drain pipe 8 by means of pipe 26. The overflow pipe 27 is connected to the drain fitting 21 for discharging into the chamber 22. With this arrangement, the trap 25 is always accessible by way of the drain opening 15 for cleaning and the like without the necessity of removing wall panels and the like, as has been customary in the past.

The wall 28 of the tub 4 is provided with an 10 overflow opening 29. A combined overflow and supply nozzle fitting 30 is mounted on the inside of the wall 28, while a combined overflow and supply fitting 31 is mounted on the outside of the wall 28, the fittings being held in clamping 15 engagement with the wall by means of the relatively short horizontal pipe 32. A gasket 33 is disposed between the wall 28 and the fitting 31 for preventing leakage of the overflow.

The interior fitting 30 is provided with a supply nozzle 42 and an overflow passage 43 which communicates with the overflow opening 29 in the wall of the tub.

The external fitting 31 is provided with a supply chamber 34 and an overflow chamber 35, the latter opening to the overflow opening in the tub wall and discharging into the overflow pipe 27 which is connected thereto. The water supply pipe 11 is connected to the external fitting 31 for delivering water to the chamber 34 which in turn 30 delivers it to the supply nozzle 42 by way of the relatively short exit supply pipe 32. The overflow passes through the passage 43 of the interior fitting, chamber 35 of the exterior fitting, overflow pipe 27, and is discharged therefrom 35 into the chamber 22 of the drain fittings 21.

We have illustrated and described our improvements in an embodiment which we have found very practical. We have not attempted to illustrate or describe other embodiments or adaptations, as it is believed that this disclosure will enable those skilled in the art to embody or adapt our improvements as may be desired.

Having thus described our invention, what we claim as new and desire to secure by Letters Patent, is:

1. A bath tub provided with a bottom having a drain opening surrounded by an annular recess, a bushing disposed through said opening and provided with an annular flange received by said 50 recess, a strainer or drain plate removably secured to said flange, a drain fitting threaded to said bushing and having a chamber disposed directly below the drain opening, and a running trap connected to the bottom of the fitting with 55

- the trap entrance opening to said chamber for cleaning therethrough, the drain opening and said chamber being relatively large compared to said trap entrance.
5. 2. The combination with a floor, a hollow wall, a drain pipe arranged within said wall, and a bath tub disposed on said floor adjacent said wall and having a drain opening provided with an annular recess, of a bushing disposed through said opening and having an annular flange fitting within said recess, a strainer or drain plate removably secured to said flange, a drain fitting threaded on said bushing and having a chamber
- disposed directly below said drain opening, the floor having an opening for the passage of said fitting, an overflow for the tub discharging into said chamber, and a running trap connecting the bottom of said fitting to said drain pipe with the trap entrance in substantially vertical alignment with said drain opening so that the trap is readily accessible by way of the drain opening for cleaning, the drain opening and said chamber being relatively large compared to the trap entrance for this purpose.

ALBERT V. REDMOND.
